ELEVATOR SYSTEM.

1,184,169.

Specification of Letters Patent.

Patented May 23, 1916.

Application filed August 7, 1909. Serial No. 511,680.

To all whom it may concern:

Be it known that I, EDWARD L. DUNN, a citizen of the United States, residing at Worcester, in the county of Worcester and State of Massachusetts, have invented certain new and useful Improvements in Elevator Systems, of which the following is a full, clear, and exact specification.

This invention relates to automatic elevator systems and has particular reference to automatic signaling systems for dumbwaiters or elevators, wherein the car can be sent to any predetermined floor and automatically stopped when the floor is reached. Where a dumbwaiter or elevator system has a considerable number of stops to make and a long run, necessitating several cars, it has been found that more satisfactory operating results can be obtained where the machines are all controlled by a single operator. In order to enable the operator to control one or more cars at the greatest efficiency, it is desirable to provide a signaling system, and such signaling system should embody means whereby delays, not only at the operating station, but at the floors, may be avoided; and also a system not required to be manually controlled.

In carrying out the invention, I have provided an automatic signaling system for such elevator systems wherein the operator can be signaled from any station when a car is desired for use, who will thereupon send a car to that floor. The arrival of the car at the floor will be indicated to the operator and also to the attendant on the floor, and when the attendant is through with the car, and indication of such fact will be made to the operator so that he can send the car to the next station, or back to a central distributing station. I have provided herein such a signaling system in combination with an automatic elevator wherein at the operating station is provided an indicator for each car showing the progress of the various cars from floor to floor, an annunciator showing the floors at which the car is desired, an audible signal in addition to the visual annunciator for attracting the attention of the operator; and at the respective

stations, signals, preferably audible, for notifying the attendant of the arrival of the car, the whole being arranged to be automatically controlled by the opening and closing of the well-room doors so that the operator need pay no attention to the re-setting of the signals, but simply to the signals themselves, and will at all times know just where each car is. The doors themselves, may be unlocked automatically by the stopping of the car, so that the system will become more completely automatic. By such a system, delays at the floors and the operating station will be very much reduced, and a greater efficiency of the whole installation obtained, as the operator will always know the condition of each car, and have nothing to do with restoring the annunciator or signals.

The invention, with respect to one form thereof, is shown in the accompanying diagram, wherein is shown an automatic signaling system for two machines having each three stops, the motor circuits being omitted for the sake of clearness, and also the control for one machine.

D¹, U¹ and D², U², represent the main switch down and up solenoids of two machines which will be hereinafter referred to as No. 1 machine and No. 2 machine respectively, and I will first briefly describe the starting and stopping system for No. 1 machine, that for No. 2 machine, and as many others as may be desired being similar, but omitted for the sake of clearness.

S¹, S² represent starting switches for the two machines, located preferably at a control station distant from the cars and the floors to which the cars run, and also at this control station are located signals for attracting the attention of the operator when a car is desired by the attendant at any floor, and signals for at all times indicating to the operator the locations of the various cars, and their condition, whether in service, or ready for service.

T¹ represents a main line switch, from which a wire H leads to up and down automatics L and M. From automatic M a wire H² leads to a movable contact H⁴, operated

by the switch arm P to close circuit at H⁵, thence wire to down direction magnet K¹, thence to negative side of switch T¹. The switch H⁴ is only momentarily closed, being opened automatically by means not necessary to be described herein, but the energization of magnet K¹, closes contacts J⁸ and thereby energizes main switch magnet D¹, closing the main motor circuit and starting the car downward. In similar manner, the up magnet K is controlled by a switch H⁴ and contact H⁶ to send the car up, it being understood that one or the other of these switches is closed whenever the pointer P is moved. In order to stop the car at the predetermined floor, an arm O traveling with the car completes a stop circuit from a contact N (closed whenever the main switch is closed) through one or the other of wires, R, R¹, R², to corresponding contacts controlled by the starting switch P, and bridged by the switch to negative side of line through resistance Y. When this circuit is closed, the magnets are short circuited, thereby opening the main switch and stopping the machine. It will be seen that the switches J⁷, J⁸, close maintaining circuits, which hold the magnets energized, after the switches H⁴ have opened. Also in a circuit to be controlled simultaneously with the magnets may be placed a door unlocking magnet Q, to unlock the door and permit it to be opened by the attendant when the car has reached that floor, as shown in my Patent No. 987,673, dated March 21, 1911. Or other means will be provided for unlocking the door at which the car is to stop. This is desirable, in order that the signals for the attendant and operator may be properly operated. By the combination of door unlocking means controlled by the stopping of the car, and the signal releasing devices controlled by the door, the system both as to signals and control will be entirely automatic, and the operator will at all times know accurately, the condition of the system, and of each car.

F¹, F², F³ represent door switches for machine No. 1, and F⁴, F⁵, F⁶ corresponding door switches for machine No. 2.

X¹ is a switch which opens as the main switch solenoid D¹ is energized, and X² a corresponding switch which operates in the same manner at machine No. 2 when solenoid D² is energized.

First describing the indicators, which are alike for each machine, there is provided a cross-head E¹, which is caused to move across the faces of the sets of stationary contacts 1, 2, 3, G¹, H¹, H², H³, G², G³, J¹, J², J³, as the machine moves in one or the other direction. These commutators will ordinarily be driven by a worm shaft and traveling nut as is well understood. In a similar manner, the cross-head E² moves over corre-

sponding sets of contacts 1, 2, 3, G², Y¹, Y², Y³, G⁴, G⁶, J⁴, J⁵, J⁶, for machine No. 2, and there will be as many similar sets of commutators and brushes as there are machines.

T is a line switch adapted to be connected with a source of low voltage current, and from the positive terminal of switch T a wire W¹ supplies current to the contacts G¹, G², etc. From G¹ a jumper on the brush E¹ conducts the current to the contacts 1, 2, 3, and thence the current passes through wires W² to an indicator I for machine No. 1, and thence by return wire W³ to the negative side of switch T. The indicator I preferably comprises a series of flashlights, one for each floor, which will be lighted one after another as the brush E¹ travels over the contacts 1, 2, 3. For machine No. 2, a similar indicator I² supplied by wires W⁴ acts in the same manner. In the position shown, car No. 1, is at the first floor, and car No. 2 at the second floor.

It is desirable to provide an audible signal to attract the attention of the operator to the annunciator signal, and I will now describe the annunciator circuits and then the audible signal circuits. From the positive side of switch T, wire W⁵ is connected to a bell or buzzer B located at or adjacent the operating station and starting switch, and from the bell B, wire W⁶ leads to a series of floor push buttons P¹, P², P³. One of these buttons will be at each floor in a system where the cars are used to carry material from a central distributing station to the several floors, or from these several floors back to the central station, or where cars run light in either direction between the central station and the respective floors. Where it is desired to call a car to one floor to receive a load to be taken to another floor, without sending the car back to the central station, a complete set of buttons may be installed at each floor, so that the operator, when at floor 2, having received car No. 2, may load it and then by pressing button No. 3, signal the operator to send this car to floor No. 3. It has been found in practice, however, with dumbwaiter systems such as this invention is particularly adapted for, that greater efficiency is obtained by operating the cars from a central station, since in hotels, for instance, time is saved by sending different cars to different floors, rather than having one car stop at a number of different floors to pick up or leave material. In most instances, therefore, it will only be necessary to have a single button at each floor. The circuit of push button P¹, for instance, leads by wire W⁷ to a lighting magnet B¹, and thence by wire W⁸ to the negative side of switch T. The circuit of push button P² similarly leads to a lighting magnet B² to wire W⁸, and P³ to lighting mag-

net B³, there being as many magnets B¹, etc., as there are floors. Upon magnet B³ being energized, its armature closes a circuit from wire W¹ to contacts X³, X⁴, to wire W⁷, and 5 thence across contacts X⁵, X⁶ to wire W⁷, so that magnet B³ will remain energized, even after the push button circuit has been opened, as it is only momentarily held closed. The opening of the push button circuit, 10 does however, release the bell or buzzer. At the same time that the holding circuit of magnet B³ is closed at contacts X³ and X⁴, current is supplied to wire W¹⁵ and thence to the light 3 of the annunciator A, 15 the remainder of the circuit being through wire W³ to the negative side of switch T. It thus appears that upon the momentary closing of a push button one or the other of magnets B¹, etc., is energized and a corresponding 20 indication made at the annunciator A, from which the operator knows that a car is desired at that floor. At the same time the alarm B sounds, as will be understood, since the alarm is at first in series 25 with the magnets B¹, B², etc., but a single alarm and set of push buttons being required for any number of floors and machines. Assuming that the operator's attention has been attracted by the bell and he has despatched No. 1 car to the third floor, contacts X¹ are closed, contacts X⁷ are opened by the closing of the main switch, and the brush E¹ is moving toward No. 3 to contacts J³, H³. As contact H² is engaged the 30 floor bell does not ring, owing to the open circuit at contacts X⁷, but as the machine stops at the third floor, the bell B⁶ is in circuit from positive side of switch T through wire W⁵ to bell B⁶, to wire W¹⁰, to contacts 35 H³, G³ by a jumper on blade E¹, wire W¹¹ to contacts X⁷, X⁹ which are now closed by the opening of the main switch, wire W⁸ to the negative side of switch T. When the contacts X¹ were closed by the closing 40 of the main switch in either direction, the controlling magnet A¹ was energized, its circuit being through contacts X¹ and wire W¹², resistance R to negative side of switch T¹. As contacts X¹ open and the machine 45 stops, the magnet A¹ is not deenergized, as it receives current through the door switches F¹, F², F³ and magnet switch contacts X¹⁰ controlled by the magnet A¹. The floor bell B⁶, therefore continues ringing until the 50 door switch circuit is opened, which deenergizes the magnet A¹ and opens the bell circuit at contact X⁹. When the door is closed again, the bell does not ring as the magnet A¹ can only receive starting current 55 through contacts X¹, which remain open until the main switch closes, but the annunciator light is automatically extinguished by the closing of the door as follows: As the contacts X¹¹ are now connected, 60 the high voltage current passes from posi- tive side of switch T¹ through door switches F¹, F², F³, contacts X¹¹ and wire W¹⁷, thence to magnet A², and resistance R to the negative side of the line. This energizes the magnet A² and closes contacts X¹³, X¹⁴, 70 making a circuit momentarily through extinguishing magnet C³, deenergizing the lighting magnet B³, thereby opening the annunciator circuit. It will therefore be seen that the annunciator circuit is not affected 75 by the stopping, and that the light remains lighted while the door is open, thus notifying the operator that the door is open at the floor where the car is stopped only, and as soon as the door is closed the extinguished 80 light shows that the machine can now be operated safely. The circuit of extinguishing magnet C³ extends from positive side of switch T through wire W¹, contacts X³, X⁴, wire W⁹, extinguishing magnet C³, wire 85 W¹³, contacts J³, G⁵, wire W¹⁴, controlling magnet contacts X¹³, X¹⁴, wire W⁸, to the negative side of switch T. When the extinguishing magnet C³ is energized the circuit of lighting magnet B³ is 90 opened at contacts X⁵, X⁶, and the lighting magnet B³ thus opens the circuit of extinguishing magnet C³ at contacts X³, X⁴, as well as the annunciator light circuit. Controlling magnet A² remains in circuit while 95 the machine is at rest, but when the machine starts, it is deenergized by the opening of contacts X¹¹. It will therefore be seen that the magnet A¹ sets the floor bell circuit to be completed at the proper floor by the brush 100 E¹ bridging contacts H¹, H² or H³ and contacts G³, and that this circuit is opened by the opening of the door, but that the annunciator circuit at the operator's station remains in condition to give an indication not 105 only while the machine is at rest with the door closed, but while the door is open, being only extinguished when the door is closed after having once been opened. The other circuits for different floors and different 110 machines will be the same as those just described, and particular reference and explanation need not be made thereto. In the event of two cars arriving at the same floor simultaneously, the bell at that floor would 115 ring until both the doors were opened, as the signal machines are cross-connected. It is thought that the advantages of the system will be fully understood from the foregoing description, wherein it will be 120 seen that the system is completely automatic in operation after the floor push buttons have been operated. While bells have been shown at the various floors to notify the attendants of the arrival of the cars, in many 125 instances pilot lights may be shown where the noise of bells and buzzers would be objectionable. Such a system has a number of advantages, of which the principal one is that the attendants are automatically noti- 130

fied that a car is waiting, and the operator is likewise automatically notified when the attendant is through with the car, while at the same time the annunciator is restored. Thus 5 the operator does not have to give attention to the annunciator, as each individual car takes care of its own annunciator, and there is no loss of time at the floors or at the operating station.

10 Having thus described my invention, what I claim as new and desire to secure by Letters Patent is:

1. The combination in an elevator system, of means for starting the car and automatically stopping it at a predetermined floor, a visual call signal for indicating the destination of the car, a signal at the floor for automatically indicating the arrival of the car at said floor, a well door, means whereby the 15 opening of the door releases said floor signal, and means whereby the closing of said door releases said call signal.

2. The combination in an elevator system, of means for starting and automatically 20 stopping the car at a predetermined floor from a distant point, and flashlight means for indicating automatically to the operator the location of the car at all times.

3. The combination in an elevator system, of means for starting and automatically stopping the car at a predetermined floor from a distant point, means for indicating at the floor the arrival of the car, and means automatically indicating at the controlling 35 point the location of the car at all times.

4. The combination in an elevator system, of means for starting and automatically stopping the car from a distant point, flashlight means adjacent the starting means for 40 indicating the location of the car, a flashlight signal corresponding to each floor adjacent the starting means, means for operating said signals, and means whereby the floor attendant causes said signals corresponding to his 45 floor to be canceled.

5. The combination in an elevator system, of means for controlling the car from a distance, a call signal for indicating to the operator at the control station the desired destination of the car, and means whereby the 50 call signal is restored independently of the operator.

6. The combination in an elevator system, of means for controlling the car from a distance, a visual call signal adjacent said controlling means for indicating to the operator at the control station the desired destination of the car, and means whereby the call signal is automatically restored only after the car 60 has stopped at the predetermined floor.

7. The combination in an elevator system, of means for controlling the car from a distance, a call signal adjacent said controlling means for indicating to the operator the desired destination of the car, means

for indicating at the floor the arrival of the car, and means controlled by the well door for releasing both signals.

8. The combination in an elevator system, with a plurality of cars, of means for controlling said cars from a distance, a single call signal corresponding to each floor adjacent said controlling means for indicating to the operator the desired destination of a car, and means whereby said signal 75 is released upon the arrival of one of said cars at said floor.

9. The combination in an elevator system, with a plurality of cars, of means for controlling said cars from a distance, a single 80 call signal corresponding to each floor located adjacent said controlling means for indicating the desired destination of a car, a signal for each car to indicate at the floor the arrival of the car, means for releasing 85 the arrival signal upon opening the well door, and means for releasing the call signal upon closing the well door.

10. The combination in an elevator system, of means for controlling the elevator 90 car from a distance, a push button controlled call signal adjacent the controlling means, and a second call signal adjacent the controlling means controlled by said push button.

11. The combination in an elevator system, of means for controlling the elevator car from a distance, a plurality of call signals adjacent said controlling means, a push button circuit for operating both signals, 100 and means whereby the release of one call signal is controlled by the stopping of the car.

12. The combination in an elevator system, of means for controlling the elevator 105 car from a distance, an audible signal adjacent the starting means, a visual signal corresponding to the floor to which the car is to be sent, means for actuating both signals, means for releasing the audible signal, 110 and means controlled by the stopping of the car for releasing the visual signal.

13. The combination in a multiple elevator system, of means for controlling the elevator cars from a distance, a signal adjacent 115 the starting means and adapted to be energized from any floor, a set of signals corresponding to each floor also adjacent the starting means, means for energizing said signals, means for releasing said first signal, and means controlled by the stopping of the car for releasing said floor signal.

14. The combination in a multiple elevator system, of means for controlling the car from a distance, a signal adjacent the 125 starting means adapted to be energized from any floor, a set of signals corresponding to each floor adjacent said starting means, means for energizing said signals, a signal at the floor indicating the arrival of the car, 130

means for releasing said first signal, and means controlled by the stopping of the car for releasing said other signals.

15. The combination in a multiple elevator system, of means for controlling the car from a distance, a signal adjacent the starting means adapted to be energized from any floor, a set of signals corresponding to each floor adjacent said starting means, means for energizing said signals, a signal at the floor indicating the arrival of the car, means for releasing said first signal, means for releasing said floor signal upon the opening of a well door, and means for releasing said second signal upon the closing of the well door.

16. The combination in an elevator system, of manual means located at one of the floors for starting the car and stopping it automatically at a predetermined floor, an indicator adjacent said controlling means for indicating at all times the position of the car, a call annunciator adjacent said starting means having signals corresponding to the several floors, together with push buttons at the several floors for energizing

the respective signals to indicate the desired destination of the car, and means for automatically restoring said annunciator when the car reaches the corresponding floor.

17. The combination in an elevator system, of means located at one of the floors for starting the car and automatically stopping it at a predetermined floor, an annunciator adjacent said controlling means having signals corresponding to the respective floors, switches at said respective floors and circuits connected to said signals for indicating the desired destination of the car, a signal at the floor for automatically indicating the arrival of the car, means controlled by an attendant at the floor whereby said arrival signal is released upon opening of the well door, and means whereby said call signal at the control station is restored upon closing of the door.

In testimony whereof I affix my signature, in presence of two witnesses.

EDWARD L. DUNN.
